UNITED STATES PATENT OFFICE.

GEORGE HILL, OF TUCAPAU, SOUTH CAROLINA, ASSIGNOR OF ONE-HALF TO
ALFRED MOORE, OF TUCAPAU, SOUTH CAROLINA.

SPINDLE AND BEARING.

SPECIFICATION forming part of Letters Patent No. 718,349, dated January 13, 1903.

Application filed December 28, 1901. Serial No. 87,587. (No model.)

To all whom it may concern:

Be it known that I, GEORGE HILL, a citizen of the United States of America, residing at Tucapau, in the county of Spartanburg and State of South Carolina, have invented certain new and useful Improvements in Spindles and Bearings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain new and useful improvements in spindles and bearings, the object being to provide a spindle-support with means for lubricating the bearings upon which the whirl rotates, the construction of the parts being such that the spindle is carried by the whirl and is maintained out of engagement with the bolster upon which the whirl turns, means being provided for lubricating the bearings without interfering with or stopping the spindle, the lubricating means including a hollow bolster and a chamber for the lubricant, as will be hereinafter set forth, and specifically pointed out in the claims.

In the accompanying drawings, Figure 1 is a side elevation of a spindle, its whirl, and support constructed in accordance with my invention. Fig. 2 is a vertical section showing a construction by which the oil is automatically supplied to the bearings. Fig. 3 is a vertical section of a modification which is designed for use with a heavy lubricant, as grease. Fig. 4 is a sectional view of a modified form of the main support, the lower end thereof being closed by a plug. Fig. 5 is a modification of the bolster shown by Fig. 2, in which instance the lower bearing is formed integral with the bolster, and the skein or sleeve which carries the whirl is provided with separable bearings.

In the drawings, A indicates a part of the frame or rail of a spinning-machine which has openings which receive the support or casting B, the same having a hollow depending portion which extends through the openings in the rail, said part being externally

threaded to receive a nut b, which holds the support upon the rail. The support B has a recess into which depends the lower part of the whirl. The bolster C is hollow and communicates with the oil-chamber B' in the part B.

The upper portion of the oil-chamber B' is threaded to engage threads c on the lower end of the bolster C. In the construction shown in Figs. 2, 4, and 5 the support B has an oil-passage c', which intersects the circular cavity or recess and leads the oil to the chamber B', the oil-passage being enlarged at its outer end to provide an oil-cup, which may be closed by a suitable cover. The bolster C has a shoulder c², which engages a fixed part of the structure, and the upper end of the bolster is externally threaded to receive a ball-bearing and lock-nut d. The spindle-carrying whirl D at its upper end has a tapered recess or opening in which is secured the tapered butt of the spindle, and said whirl has the usual cup and pulley. The whirl, which is placed over the bolster, has ball raceways or bearings e e', with which the balls or spherical rollers engage, they also engaging ball raceways or bearings f f' of the bolster.

In the construction shown in Fig. 2 the lower portion of the bolster carries a bearing F, located between the shoulder c² and the bottom of the recess in the part B. The upper portion of the bolster carries an adjustable bearing F', the threads of which engage the threads on the upper end of the bolster, the bearing being locked when adjusted by the nut d. The whirl D has removably attached thereto a sleeve or skein G, the upper and lower ends being beveled to provide bearings e e'. The hollow bolster is provided above its lower bearing with an aperture through which is passed a wick for feeding the lubricant to the lower bearing, the upper bearing being fed by a wick C', which is passed through the hollow bolster and depends therefrom into the oil-chamber B'. The oil-chamber may be filled through the passage c' and by capillary attraction is fed to the ball-bearings. Any surplus oil flows into the recess in the casting B and is fed therefrom back into the chamber.

When it is desired to separate the parts for

adjusting or cleaning, the set-screw is disengaged from the sleeve. The whirl may then be raised from the sleeve to expose the bearings. The bolster can be separated from its support when it is desirable to have access to the oil-chamber. In the construction shown in Figs. 2, 4, and 5 the device is more particularly intended for the automatic supply of light lubricating-oils, and the construction is such that in practice there can be no gyratory motion given to the spindle.

The construction shown in Fig. 3 provides for the manual feed of a heavy lubricant, as grease. A hollow bolster is used, the ball-race-ways of the bolster being integral, and through such bolster are apertures through which the grease is forced upon the bearings. The bearings carried by the whirl are in separate pieces, the lower one being adjustably secured in place and locked by a screw. The opening through the part B is adapted to receive a sleeve with which the hollow bolster is connected, said sleeve being internally threaded to receive a piston or follower I, which can be turned to force the grease from the chamber B' through the openings upon the bearings. The sleeve or cylinder extends beyond the depending portion of the part B and is threaded to receive a nut h. The upper end of the bolster has a threaded stem, over which is placed a washer, which retains the upper set of balls, the washer being held in place by a nut d. To remove the whirl and bolster from the part B, the nut h is taken off and the sleeve is withdrawn. The lower bearing may be then taken off and the bolster separated from the whirl.

It will be seen that in the practical embodiment of my invention I can by slight modification of the parts use either a light or heavy lubricant and that many of the parts are common to both forms of the invention.

I claim—

1. A spindle bearing and support comprising a part having a chamber for a lubricant, a hollow bolster with bearings, the bolster being removably connected to the part having the chamber, a whirl to the upper end of which the spindle is attached, bearings carried within the balls interposed between the bolster and bearings and means for taking the lubricant from the oil-chamber through the bolster to the bearings, substantially as shown.

2. The combination in a spindle and bearing, of a whirl having bearings and a pulley with converging faces on the outside between the bearings, a hollow bolster with bearings, balls between the bearings of the whirl and bolster, a chamber for the reception of lubricating material, the bolster being connected to such chamber, and means for supplying lu-

bricant through the hollow bolster to the bearings for the balls, substantially as shown.

3. In combination with a spindle, its whirl, bolster and bearings, of a support having in its upper face a recess and below the recess a chamber for a lubricant, a hollow bolster which is attached to the support, bearings near the upper and lower ends of the bolster, a whirl having bearings which correspond with those of the bolster, balls between the bearings, and means for supplying the lubricant from the chamber to the aforesaid bearings, substantially as shown.

4. In a spindle-support, the combination of a support having an oil-chamber and a recess above said chamber, an oil-passage from the exterior of the support to the oil-chamber said passage being in communication with the recess, a hollow bolster attached to the support, a whirl mounted on the bolster, and a wick for carrying the oil from the oil-chamber to the bearings between the bolster and whirl, substantially as shown.

5. In a spindle-support, the combination of a support which is detachably connected to the frame or rail of a spinning-machine, an oil-chamber in said detachable support, a hollow bolster attached to the support and provided with a fixed and with an adjustable bearing, balls between the bearings, a wick which extends through the bolster and into the oil-chamber, a whirl having interiorly a sleeve or skein between the bearings on the bolster, and externally a pulley between the bearings; together with a spindle which is carried by the upper end of the whirl, substantially as shown.

6. In a spindle-support, the combination of a support having an oil-chamber, a recess in the upper portion of the support, an oil-cup in the exterior of the support, a passage which connects the recess with the oil-chamber and with the oil-cup, a hollow spindle connected to the support, bearings on the spindle, oil-duets through the spindle for leading oil to the bearings, a whirl, the lower portion of which extends into the recess in the upper portion of the support, a spindle carried by the upper end of the whirl, bearings removably connected to the whirl, a pulley on the whirl between the bearings, and a circular series of balls placed so as to be engaged by the bearings, substantially as shown and for the purpose set forth.

In testimony whereof I have hereunto set my hand in presence of two subscribing witnesses.

GEO. HILL.
